UNITED STATES PATENT OFFICE

EDWARD L. CHOTT, OF CHICAGO, ILLINOIS

MORTAR AND PESTLE

Application filed November 13, 1929. Serial No. 406,753.

This invention relates to mortars and pestles, and more particularly to devices of this character for preparing dental amalgams and other characteristically similar mixtures.

As is well known, dental amalgams usually comprise a triturated mixture of a characteristic metal alloy and mercury. According to the customary practice, and owing to the peculiar nature of the work in which it is used, only a relatively small quantity of the amalgam is prepared at one time, and in its preparation accuracy in the proportioning of the respective ingredients and the thorough mixing and amalgamation thereof are absolutely essential to secure the proper results.

The principal object of the present invention is to produce a peculiarly formed mortar and cooperating pestle, more particularly for use in the production of dental amalgams and the like, but without limitation to such use, in which provision is made for a full and complete contacting or triturating surface and for preventing displacement of the mercury or other ingredient up the side wall of the mortar, whereby to secure a better and quicker result; to provide for readily observing the condition of the material in the course of trituration; and to attain certain other advantages as will be hereinafter more fully set forth.

The invention consists in the novel construction and arrangement of the mortar and pestle, and in their cooperative action, as will be hereinafter described and pointed out with particularity in the appended claims.

In the accompanying drawing, forming a part of this specification, and illustrating a practical adaptation of the invention,—

Fig. 1 is a perspective view of the mortar with the pestle supported therein;

Fig. 2 is a fragmentary detail view, on an enlarged scale, the mortar being shown in vertical cross section, and the lower portion of the pestle inserted therein being shown in elevation, the handle portion of the pestle being broken away and shown partly in section; and

Fig. 3 is a horizontal section, taken on or about the line 3—3 of Fig. 2.

Referring now to the drawing, the numeral 5 designates generally the mortar and 6 the pestle. As shown, the bottom of the mortar 5 is flattened on its outer face, as at 7, and its side walls are upwardly convergent on the outside, as at 8. The inner face 9 of the bottom of the mortar is flattened and the upper portion 10 of the inner face of the side wall is truly cylindrical or perpendicular to said bottom face 9. In the lower portion of the mortar is provided an annular groove 11, which undercuts the inner face 10 of the side wall and merges with the inner face 9 of the bottom wall of the mortar, said annular groove being cross-curved, as at 12, on a radius equal to one-half the diameter of a spherical head 13 provided at the end of the reduced neck portion 14 of the pestle 6.

According to the present invention and for the objects to be attained thereby, the groove 11 of the mortar and the spherical head 13 of the pestle are correspondingly formed with accuracy, and for the purposes 75 for which the invention is more particularly intended, the mortar and pestle are preferably made of a metal known as "strainless steel," but the same may be made of other suitable or approved non-corrosive material. 80

Preferably, the handle portion 15 of the pestle is made hollow, so that it may be of sufficient size to be held firmly in the hand but light in weight so as not to be topheavy. The handle portion 15 is also preferably provided with diametrically opposite projections 16 which, as a convenience in manufacture, may be a pin secured as by a drive fit or otherwise in diametrically aligned apertures provided therefor in the hollowed portion of the handle, said projections 16 preventing the pestle from rolling on a table or other flat supporting surface.

In the use of the mortar and pestle of the present invention the mercury and alloy to 95 comprise the amalgam, the alloy in the form of filings or shavings and the mercury in a measured drop or globule, are placed in the mortar and subjected to the rolling and pressing action of the spherical head 13 of the 100

pestle in the groove 11 of the mortar. In the manipulation of the pestle the ingredients in the mortar are not ground upon the flattened portion 9 of the bottom or floor thereof, but rather with the above noted 5 action in the groove 11. By holding the mortar tilted at one side the mercury and alloy will fall together in the lowest part of the groove 11, and upon each rotation of the 10 head 13 of the pestle in the groove it will work upon and through the entire mass. When the pestle is rotated the force is naturally exerted downward and outward, and as the circumference of the spherical 15 head 13 is of a curvature corresponding to the transverse curvature of the annular groove 11, greater contact is afforded, thereby hastening the amalgamation of the mercury and alloy and resulting in an ideally smooth 20 and plastic product which is obtained by mixing and forcing the mercury into the alloy by a rolling pressure rather than by a grinding action. In mixing the amalgam in the groove 11, even when the mortar is 25 tilted at a considerable angle, the annular shoulder 17 afforded by the undercutting of the groove 11 prevents the ingredients, particularly the mercury which is more liable to do so, from working by displacement up 30 the face 10 of the mortar.

By the provision of the characteristic undercut groove 11 in the mortar and the cooperating spherical head 13 of the pestle, not only is the amalgam produced ideally 35 and with comparative rapidity, but also the condition of the product is readily observable as the treatment progresses, which is of considerable advantage, for care must be exercised so as not to over or under mix the ingredients. 40

By having the handle portion 15 of the pestle hollow, as hereinbefore described, the handle may be made sufficiently large to provide for a firm grasp in manipulating the 45 pestle, and at the same time the preponderance of the weight will be in the neck portion 14 and spherical head 13 within the mortar, so that the liability of accidentally tipping over the mortar is greatly minimized and by 50 which arrangement the mortar with the pestle therein has a tendency to right itself from the tilted position should the operator release his hold thereon in the course of preparing the amalgam or other admixture in 55 the mortar. As shown, the mortar is provided with a circumferential annular groove 18 near its bottom which enable the operator to secure a firm grasp upon the mortar whereby to hold it either in flatwise or tilted position. 60

Obviously, the device admits of considerable modification without in the least departing from the spirit and scope of the invention as defined by the appended claims. The invention, therefore, is not limited to the specific 65

construction and arrangement shown in the accompanying drawing.

Having thus described my invention, what I claim as new and desire to secure by Letters Patent is:

1. The combination of a mortar whose working cavity has a flattened bottom, a cylindrical upper wall portion, and an annular groove in its wall transversely curved and merging tangentially with said flattened bottom without interruptive protuberance and providing an annular undercut interruptive shoulder where said groove merges with the upper side wall portion of the mortar, and a pestle having a spherical head portion, said head portion being cooperative with the annular groove in said mortar, and said annular groove being transversely curved corresponding exactly to the circumferential curvature of said spherical head. 75

2. A mortar having a flat relatively thick bottom wall and an upwardly tapering annular side wall, the cavity of said mortar being grooved annularly coincident with the corner of its bottom and side walls, the groove being uniformly rounded transversely at every point, and the base portion of the mortar having an external annular groove therein. 80

3. A mortar having a flat relatively thick bottom wall and an upwardly tapering annular side wall, the cavity of said mortar being grooved annularly coincident with the corner of its bottom and side walls, the groove being curved on the same radius transversely and merging at its lower side tangentially with the bottom face of the cavity without interruptive protuberance at any point, the upper side of said groove merging at every point with the face of the side wall of the cavity in an undercut shoulder, the base portion of the mortar being provided with an external annular groove. 95

In testimony whereof I have signed my name to this specification.
